DESIGN FOR A COAT AND HAT HOOK

Theodor J. C. Schirrmacher, Oakland, Calif.

Application March 19, 1934, Serial No. 51,090

Term of patent 7 years

To all whom it may concern:

Be it known that I, THEODOR J. C. SCHIRRMACHER, a citizen of the United States, residing at Oakland, in the county of Alameda, State of California, have invented a new, original, and ornamental Design for a Coat and Hat Hook, of which the following is a specification, reference being had to the accompanying drawing, forming part thereof and of which

The dominant feature of the present design is the arm A, which has its intermediate portion spaced a substantial distance forward of the intermediate portion of the main body portion of the hook, and its lower end portion bent rearwards in a direction towards said main body portion.

I claim:

The ornamental design for a coat and hat hook, as shown and described.

THEODOR J. C. SCHIRRMACHER.
